BLOCK-RESURFACING MECHANISM.

1,341,765.

Specification of Letters Patent. Patented June 1, 1920.

Application filed November 17, 1916. Serial No. 131,933.

To all whom it may concern:

Be it known that I, RALPH C. SIMMONS, a citizen of the United States, residing at Beverly, in the county of Essex and State of Massachusetts, have invented certain Improvements in Block-Resurfacing Mechanisms, of which the following description, in connection with the accompanying drawings, is a specification, like reference characters on the drawings indicating like parts in the several figures.

This invention relates to machines for cutting sheet material, and particularly to mechanism for use in resurfacing the cutting blocks of such machines. The invention is herein shown in its application to a machine for dieing out relatively thin sheet material such as upper stock for use in the manufacture of boots and shoes, the illustrative type of machine being known as the clicking machine of which an example is shown and described in United States Letters Patent No. 921,503, granted on May 11, 1909 upon the application of Arthur Bates. It will be apparent, however, from the following description that the utility of the invention is not restricted to machines of this particular type, and that the invention in its broader aspects is applicable to cutting machines of various types such, for example, as machines for dieing out soles.

In machines which perform the cutting operation by means of a die, or the like, and a coöperating cutting block, it is important for the best results that the block, when made of wood or of material having similar characteristics, be resurfaced frequently in order to present a comparatively smooth and even surface to the cutting edge of the die. If this is not done it is often impossible to sever a blank completely at a single operation of the machine, and the blanks, moreover, are likely to be left with ragged edges. In the clicking machine it is particularly important to keep the block properly surfaced in order to avoid the danger of springing out of shape the comparatively light dies that are used with this machine.

It has been the usual practice to resurface cutting blocks by the use of a hand operated tool while the block remains in place on the machine, thus avoiding the difficulty and loss of time involved in removing the block and planing it in a special machine as well as

the expense of providing and maintaining such a planing machine. By reason, however, of the hard and resistant character of the material in cutting blocks, such a hand operation is laborious and comparatively slow, and consequently operators are likely to neglect the resurfacing of the blocks. It is difficult, moreover, to produce by the use of a hand tool a perfectly even surface over the entire area of the block. It has been proposed, as an alternative to the use of hand tools, to resurface the block by means of mechanism attached to the machine and arranged to be operated either manually or by power; but such mechanism as heretofore proposed has been open to various objections, arising principally from difficulty in manipulation of the mechanism or inconvenience in the use of special driving connections, and consequently has not been entirely satisfactory for the purpose in view.

It is an important object of this invention to provide block resurfacing means of simple construction which may be readily applied to a machine in position for use and effectively operated to form a smooth and regular surface upon the block. To this end, a feature of the invention consists in a construction and arrangement of resurfacing means such as to cause said means to receive an operative movement in consequence of relative movement of the block and the co-operating presser member in the direction to effect a cutting operation, the resurfacing means, in the construction shown, comprising a tool operatively movable in a direction transverse to the direction of such relative movement of the block and the presser member. In the application of the invention to the clicking machine the usual relative lateral movement of the presser member and the block are utilized to cause the resurfacing means to assume an operative relation to different portions of the surface of the block in succession, and for this purpose the resurfacing means is conveniently mounted on the presser member. In the usual construction, wherein the presser member swings over the block into operative relation to different portions of the surface and has also an operative movement toward the block, both movements of the presser member are thus utilized, the one to bring the resurfacing tool into operative relation to a portion of the

block that requires resurfacing and the other to cause the tool to cut the block.

A further feature of the invention consists in novel means for regulating the depth of the cut of the resurfacing tool. This feature includes the provision of means for making preliminarily a relatively narrow cut to the required depth across the block, this cut being utilized to determine the depth of the cut of the resurfacing tool in its operation upon different portions of the block.

These and other features of the invention, including certain details of construction and combinations of parts, will now be described 15 with reference to the accompanying drawings and pointed out in the claims.

In the drawings,

Figure 1 is a plan view showing a portion of a clicking machine and illustrating the 20 application to such machine of mechanism constructed in accordance with this invention,

Fig. 2 is a view in side elevation of the structure shown in Fig. 1, the cutting block 25 being shown in vertical section,

Fig. 3 shows on an enlarged scale a portion of the mechanism from the same point of view as Fig. 2,

Fig. 4 is a view in vertical section on the 30 line 4—4 of Figs. 1 and 2, showing the presser member and the resurfacing means attached thereto,

Fig. 5 is a vertical section through the means for forming the preliminary cut in 35 the block,

Fig. 6 is a vertical section through the means whereby the depth of the cut of the resurfacing tool is determined by reference to the cut formed by the device shown in 40 Fig. 5,

Fig. 7 illustrates the construction of an alternative form of resurfacing tool, and

Fig. 8 is a vertical section similar to Fig. 6, showing the form of tool illustrated in 45 Fig. 7.

The clicking machine shown includes the usual presser member or arm 2 which is secured to the vertical post 4 at the rear of the cutting block or bed 6, the post being 50 mounted for turning movement to permit the presser member to swing to different positions over the block corresponding to different locations of the die upon the stock and for reciprocating movement vertically 55 to cause the presser member to engage the die and effect the cutting operation. It will be understood that the operative vertical movement of the presser member takes place upon the actuation of the usual clutch 60 through connections extending from the starting handle 8, this handle being utilized also for the purpose of swinging the presser member over the block.

In the construction shown the block 65 resurfacing mechanism is constructed for at-

tachment to the presser member 2. To this end the mechanism comprises two castings 10 and 12 provided respectively with portions shaped to underlie and engage the lower surface of the member 2 adjacent to 70 the sides of the member and also with means for fixing their relation to the side edges of the member. Set screws 14 in the casting 10 engage the upper surface of the member 2 to hold the casting in place, and threaded in 75 the casting also are tie rods 16 which serve to clamp the casting 12 against the opposite side of the member 2 as well as to insure against lateral displacement of the casting 10 on the member.

Pivoted on the casting 10 in recesses formed in the side of the casting are a series of links 18 on the lower ends of which is hung a cutting tool 20 having teeth 22 that project forwardly or in the direction of the 85 front end of the presser member 2. A spring 24 connected at one end to a lug 26, on the casting 10 and at its other end to a threaded rod 28 in a bracket 30 on the front end of the tool 20 serves normally to hold 90 the tool 20 in a retracted position in which the links 18 are more nearly vertical than when positioned as shown in Fig. 2 although still inclined in a forward direction. A nut 32 threaded on the rod 28 is adjustable to 95 vary the tension of the spring 24, and an adjustable stop 34 in the bracket 30 serves by engagement with the front end of the casting 10 to determine the normal position of the tool 20 when the presser member 2 is 100 in its uppermost position. It will be understood that when the member 2 is in its uppermost position the teeth 22 will be above the surface of the block, and it will now be apparent that when an operative downward 105 movement is imparted to the presser member the teeth 22 will be forced downwardly into the surface of the block and the tool 20 will also be moved forwardly by the swinging of the links 18 to cause the teeth 110 to cut across the surface of the block.

The time in the downward movement of the member 2 when the teeth 22 first engage the block and consequently the extent of forward movement of the tool 20 115 may be varied by adjustment of the stop 34.

In order to regulate the depth of the cut of the tool 20 on all portions of the block so as to form a surface extending evenly across the block, means is provided for cutting 120 preliminarily a groove across the upper surface of the block which shall serve as a guide to determine the depth of cut of the tool. This means comprises a cutting tool 36 supported in a holder 38 on the casting 12, the tool being pivoted at 40 in a cylindrical support 42 which is arranged for vertical adjustment in the holder 38 by means of a screw 44. A key screw 46 projecting within a vertical guideway in the support 130

42 prevents the support from turning and positions the support with the cutting tooth of the tool 36 directly laterally so as to render the tool effective to cut the surface 5 of the block as the presser member is swung in one direction over the block, this direction being toward the left as the parts are viewed in Fig. 1. A spring 48 serves to position the tool normally with reference to 10 swinging movement about its axis 40 to cause the cutting tooth to project effectively toward the block in the operative movement of the tool, while permitting the tool to yield against any resistance which it may 15 encounter when the presser member is swung in the reverse direction. The holder 38 is split vertically at one side and may be contracted by means of a thumb screw 50 for the purpose of holding the support 42 more 20 securely in adjusted position.

In the use of the groove cutting tool 36 the support 42 is adjusted by means of the thumb screw 44 to bring the tool into position to engage the block and the arm 20 is 25 then swung from side to side over the block to form the groove 52, the holder 42 being lowered as required to cause the tool to cut the desired depth. After the groove has 30 been cut the tool is retracted within the holder 38 to prevent its engagement with the block during the operation of the resurfacing tool 20.

The groove 52 is utilized to determine the depth of the cut of the tool 20 through the 35 provision of a stop 54 which is carried by this tool. This stop comprises a thumb screw threaded vertically in the tool 20 and adjustable to position its lower end in the required relation to the plane of the cutting 40 edges of the teeth 22, the teeth being broken away sufficiently to admit the stop. A retaining member 56 is arranged to engage the side of the stop member 54 and to be tightened by means of a thumb nut 58 to hold the 45 stop in adjusted position. It will be apparent that when the teeth 22 have cut away any portion of the block sufficiently to cause the end of the stop 54 to engage the bottom of the groove 52 the teeth will not be permitted 50 to cut any deeper into the block but will slide idly over the surface already formed. Preferably the stop will be positioned with its lower end surface in the plane of the cutting edges of the teeth 22. 55 All portions of the surface formed by the tool 20 will thus lie in a plane coincident with the plane of the bottom of the groove 52. It will be understood that the width of the groove 52 cut by the tool 36 is such as 60 to accommodate the lateral movement of the stop 54 in the operation of the tool 20, and that the stop has the same radius of movement as the tool 36 so that the stop is positioned over the groove in any position of the 65 presser member.

When a block requires resurfacing the mechanism is clamped in position on the presser member 2 in the manner explained, and the cutting tool 36 and the presser member are manipulated in the manner pointed 70 out to form a groove 52 in the block, the presser member being swung from side to side for this purpose by the use of the handle 8 or by means of a handle 60 on the front end of the casting 12. The tool 36 is 75 then withdrawn from its operative position, and the presser member 2 being positioned over any portion of the block the clutch is actuated as usual in effecting a dieing-out operation by depression of the 80 starting handle 8. By the resulting downward movement of the presser member 2 the teeth 22 are caused to engage the surface of the block and to cut across the surface in consequence of the forward movement of the 85 tool 20. As the presser member returns to its starting position the tool 20 is retracted by means of the spring 24. The operation may then be repeated, if such repetition is 90 necessary in order to cut the block to the depth determined by engagement of the stop 54 with the bottom of the groove 52. The presser member will then be swung slightly to position the tool 20 over an adjacent portion of the block which will next be operated upon in the same manner. All portions of the block having finally been resurfaced in 95 this way, the resurfacing mechanism will be removed from the presser member.

In place of the tool 20 a tool 62 constructed as shown in Figs. 7 and 8 may be used this tool comprising a plate secured detachably to a carrier 63 which is hung in the same manner as the tool 20 on the links 18, the plate having laterally directed cutting teeth 64 projecting also somewhat below the lower plane face of the plate. In the use of the tool 62 the stop 34 will preferably be so adjusted as to permit the teeth 64 to project normally as low as the plane of the cutting surface which it is desired to form, thus permitting the stop 54, the end of which will preferably lie in the plane of the lower corners or edges of the teeth 64, to rest continuously upon the surface at the bottom of the groove 52. In beginning the block resurfacing operation with this form of tool having teeth projecting on the side indicated, the presser member 2 will be positioned to cause the tool to engage the block first at the left hand rear corner, and if necessary this end of the groove 52 may be widened by the use of a hand tool, such as a rasp, in order to provide sufficient surface 125 to permit the stop 54 to engage the block with the teeth 64 positioned in engagement with the edge of the unresurfaced portion. The clutch will next be tripped as usual, the operator meanwhile subjecting the presser 130

member to a lateral pull to cause the teeth 64 to engage effectively the edge of the unresurfaced portion of the block. It will be apparent that the engagement of the stop 54 5 with the block will prevent downward movement of the tool while causing the tool to move endwise similarly to the tool 20 hereinbefore described. By operating the presser member repeatedly in this manner 10 the block may be resurfaced progressively from one side to the other, the tool 62 advancing continually over the portion already resurfaced.

Having described the invention, what I 15 claim as new and desire to secure by Letters Patent of the United States is:

1. In a machine of the class described, the combination with a presser member and a cutting block relatively movable from and 20 toward each other in a direction to perform a cutting operation, of means arranged to be operated by the presser member and the block during such relative movement and to be moved in a direction transverse to the 25 direction of said movement for resurfacing the block.

2. In a machine of the class described, the combination with a presser member and a cutting block relatively movable from and 30 toward each other in a direction to perform a cutting operation, of a block resurfacing tool mounted on the presser member, and means for causing said tool to move in a direction substantially parallel to the plane 35 of the working face of the block upon a relative cutting movement of said member and block in the first-mentioned direction.

3. In a machine of the class described, the combination with a presser member and a 40 cutting block relatively movable from and toward each other in a direction to form a cutting operation, of a block resurfacing tool, and connections between said tool and the presser member constructed and arranged 45 to cause the tool to move in a direction crosswise of the block upon a relative cutting movement of the member and the block in the first-mentioned direction.

4. In a machine of the class described, the 50 combination with a presser member and a cutting block relatively movable from and toward each other in a direction to perform a cutting operation, of a block resurfacing tool, and connections between said tool and the presser member constructed and arranged 55 to cause the tool to be moved in a direction substantially parallel to the plane of the working face of the block by engagement of the tool with the block in a relative cutting movement of the tool and the block in the first-mentioned direction.

5. In a machine of the class described, the combination with a presser member and a cutting block relatively movable in a direction 60 to perform a cutting operation, of a

block resurfacing tool, and connections between said tool and the presser member comprising links arranged with reference to the direction of said relative movement of the presser member and the block to cause 70 the tool to be moved by engagement with the block in a direction transverse to said direction of relative movement.

6. In a machine of the class described, the combination with a presser member and a cutting block relatively movable in a direction 75 to perform a cutting operation, of a block resurfacing tool, connections comprising links between said tool and the presser member, and means for positioning said tool with the links inclined to the plane of the working face of the cutting block to cause the links to swing and operate the tool in the relative movement of the presser member and the block.

7. In a machine of the class described, the combination with a presser member and a cutting block relatively movable in a direction to perform a cutting operation, of a block resurfacing tool, connections comprising links between said tool and the presser member, and a stop for positioning the tool with the links inclined to the plane of the working face of the cutting block to cause the links to swing and operate the tool upon 95 engagement of the tool with the block, said stop being adjustable to vary the length of the working stroke of the tool.

8. In a machine of the class described, the combination with a presser member and a cutting block relatively movable in a direction to perform a cutting operation, of a block resurfacing tool, connections between said tool and the presser member constructed and arranged to cause the tool to be moved in a direction substantially parallel to the plane of the working face of the block by engagement of the tool with the block in a relative cutting movement of the tool and the block, a stop for determining the starting position of the tool, and a spring for positioning the tool normally at the limit determined by said stop.

9. In a machine of the class described, the combination with a presser member and a cutting block relatively movable in a direction to perform a cutting operation, of a block resurfacing tool mounted on the presser member for reciprocatory movement in directions transverse to said direction of relative movement of the presser member and the block, said tool having a series of forwardly projecting cutting teeth, and means for positioning the tool normally at its limit of rearward movement.

10. In a machine of the class described, the combination with a presser member and a cutting block relatively movable from and toward each other in a direction to perform a cutting operation, of a block resurfacing

- tool movable into operative relation to different portions of the block, and means for operating said tool by said relative movement of the presser member and the block.
- 5 11. In a machine of the class described, the combination with a presser member and a cutting block relatively movable laterally into different operative relations to each other and also toward each other in a direction to perform a cutting operation, of a block resurfacing tool arranged to assume an operative relation to different portions of the block successively through said relative lateral movement of the presser member and the block, said tool having an operative movement crosswise of the block, and means for operating the tool through the relative cutting movement of the presser member and the block in the direction mentioned.
- 10 12. In a machine of the class described, the combination with a cutting block and a presser member constructed and arranged for movement laterally over the block and also toward the block, of block resurfacing means carried by the presser member, and means for moving the presser member toward the block and simultaneously causing the operation of the resurfacing means in the movement of the presser member toward the block.
- 15 13. In a machine of the class described, the combination with a cutting block and a presser member mounted for swinging movement over the block and also for movement toward the block, of a block resurfacing tool carried by the presser member, the connections between the tool and said member being constructed and arranged to cause the tool to be moved lengthwise of the presser member in engagement with the block when the presser member moves toward the block.
- 20 14. In a machine of the class described, the combination with a cutting block and a presser member mounted for swinging movement over the block and also for movement toward the block, of a block resurfacing tool carried by the presser member, said tool having a series of teeth extending lengthwise of the presser member, and means for causing the tool to move lengthwise of said member in engagement with the block when the presser member moves toward the block.
- 25 15. In a machine of the class described, the combination with a cutting block and a presser member movable to different positions over the block and also toward the block, of means arranged to be operated by said member in its movement toward the block for resurfacing any desired portion of the cutting surface of the block.
- 30 16. In a machine of the class described, the combination with a cutting block and a

- presser member movable to different positions over the block and also toward the block, of block resurfacing means arranged to be detachably mounted on said presser member, said means comprising a cutting tool and connections constructed and arranged to impart an operating movement to said tool upon movement of the presser member toward the block.
- 35 17. In a machine of the class described, the combination with a presser member and a cutting block relatively movable in a direction to perform a cutting operation, of means arranged to be operated by such relative movement of the presser member and the block for resurfacing different portions of the block in succession, and means controlled by the block for gaging and controlling the depth of the cut of said resurfacing means to render the surface uniform over all portions of the block.
- 40 18. In a machine of the class described, the combination with a cutting block and a presser member mounted for swinging movement over the block, of a tool connected to said member for resurfacing the block, and means also connected to said member for forming preliminarily a guiding surface on the block to determine the depth of the cut of said tool.
- 45 19. In a machine of the class described, the combination with a cutting block and a presser member mounted for swinging movement over the block, of a tool connected to said member for resurfacing different portions of the block in succession, and means movable with the tool for forming preliminarily a guiding surface extending across the block for regulating the depth of the cut of said tool.
- 50 20. In a machine of the class described, the combination with a cutting block and a presser member mounted for swinging movement over the block, of a tool connected to said member for resurfacing the block, means also connected to said member for forming preliminarily a guiding surface on the block, and means movable with the tool in engagement with said surface to limit the depth of the cut of the tool.
- 55 21. In a machine of the class described, the combination with a cutting block and a presser member mounted for swinging movement over the block, of a tool connected to said member for resurfacing different portions of the block in succession, means movable with the tool for forming preliminarily a guiding surface extending across the block, and a stop carried by the tool for engaging said surface to regulate the depth of the cut of said tool.
- 60 22. In a machine of the class described, the combination with a presser member and a cutting block relatively movable laterally into different operative relations to each

other and relatively movable also in a direction to perform a cutting operation, of means operative through said last-named relative movement of the presser member 5 and the block for resurfacing the block, means operative through the relative lateral movement of said member and block to form a guiding surface on the block for determining the depth of the cut of said resurfacing means and means acting in coöperation with said guiding surface to control the resurfacing means.

23. In a machine of the class described, the combination with a presser member and 15 a cutting block relatively movable laterally into different operative relations to each other, of a block resurfacing tool movable with the presser member, and a tool mounted on the presser member for cutting a 20 groove in the block during said relative movement of the presser member and the block to serve as a guide for determining the depth of the cut of block resurfacing means on different portions of the block.

24. In a machine of the class described, the combination with a cutting block and a presser member movable laterally over the block, of a block resurfacing tool movable with the presser member, and a tool carried 30 by the presser member for cutting a groove in the block during said movement of the presser member to serve as a guide for determining the depth of the cut of block resurfacing means on different portions of the 35 block, said tool being adjustable into or out of position to engage the block.

25. In a machine of the class described, the combination with a cutting block and a presser member movable laterally over the 40 block and also toward the block, of a tool carried by said presser member and operative in the movement of said member toward the block to resurface the block, means carried by the presser member and operative in the lateral movement of said member to form a groove extending across the block, and means carried by the tool for engaging the block in said groove to limit the depth of the cut of the tool.

26. In a machine of the class described, the combination with a cutting block and a presser member movable toward the block, of a tool arranged to be operated by the 55 presser member during the movement of the presser member toward the block for resurfacing the block, means for forming preliminarily a groove in the block, and means carried by the tool for engaging the block in said groove to limit the depth of the cut of the tool.

27. In a machine of the class described, the combination with a cutting block and a presser member movable toward the block, of a tool arranged to be operated by the 65 presser member for resurfacing the block,

the tool comprising a series of cutting teeth, means for forming preliminarily a groove in the block, and a stop carried by the tool and arranged to present a surface substantially in the plane of the cutting edges of 70 said teeth for engagement with the block in said groove to limit the depth of the cut of the tool.

28. In a machine of the class described, the combination with a cutting block and a 75 presser member relatively movable in a direction to perform a cutting operation, of a block resurfacing tool, means operated by said relative movement of the presser member and the block for causing the tool to 80 move in engagement with the block in a direction crosswise of the block, and means arranged to contact with the block for limiting the depth of the cut of the tool without preventing the movement of the tool 85 crosswise of the block.

29. In a machine of the class described, the combination with a cutting block and a presser member relatively movable in a direction to perform a cutting operation, of a 90 block resurfacing tool mounted on the presser member, means operative during a relative cutting movement of said block and presser member to cause the tool to move in a direction transverse to the direction of 95 said relative movement, means connected to the presser member for forming preliminarily a guide groove in the block, and means carried by the tool for engaging the block in said groove to limit the depth of 100 cut of the tool without preventing the movement of the tool in said transverse direction.

30. In a machine of the class described, the combination with a cutting block and a 105 presser member relatively movable with respect to each other, and power means operating to cause such relative movement, of resurfacing means arranged to operate automatically on said block upon actuation of said power means to cause such relative 110 movement for resurfacing any desired portion of the cutting surface of the block at the will of the operator.

31. In a machine of the class described, the combination with a cutting block and a 115 presser member relatively movable with respect to each other, and power means for causing such relative movement, of means under the control of the operator for resurfacing any desired portion of the block automatically actuated during said relative 120 movement of the cutting block and presser member.

32. In a machine of the class described, a cutting block, a presser member relatively 125 movable with respect to the block, means arranged to be located in different positions across the surface of the block for resurfacing the whole or any desired portion of the cutting surface of the block, and 130

power means for causing simultaneously movement of the presser member and actuation of the resurfacing means.

33. In a machine of the class described, a cutting block, a presser member relatively movable with respect of the block, means movable laterally with respect to the block for resurfacing the whole or any desired portion of the cutting surface of the block, power means for moving the presser member during the resurfacing operation, and automatically operated means for causing the operation of the resurfacing means.

34. In a machine of the class described, a cutting block, a presser member relatively movable with respect to the block, means mounted for movement laterally of the block for resurfacing the whole or any desired portion of the cutting surface of the

block, and a single shaft in the machine 20 upon rotation of which the presser member and the resurfacing means are simultaneously actuated.

35. In a machine of the class described, a cutting block, a presser member, power 25 means for moving the presser member with respect to the block, means movable laterally with respect to the block for resurfacing the whole or any desired portion of the cutting surface of the block, means for controlling 30 the movement of the resurfacing means with respect to the presser member, and means for automatically causing the operation of the resurfacing means during movement of the presser member by said power means. 35

In testimony whereof I have signed my name to this specification.

RALPH C. SIMMONS.
